UNITED STATES PATENT OFFICE.

CLIFFORD G. KING, OF PROVIDENCE, RHODE ISLAND.

CLASP.

Application filed November 21, 1922. Serial No. 602,345.

To all whom it may concern:

Be it known that I, CLIFFORD G. KING, a citizen of the United States, and a resident of Providence, in the county of Providence and State of Rhode Island, have invented a new and useful Improvement in Clasps, of which the following is a specification.

My invention relates to clasps, lingerie pins, and the like, and its object is to provide an article of this description in which the pin-tongue is secured to the front plate without the use of a pintle, and otherwise to improve and simplify the device in the manner hereinafter more fully set forth.

With the foregoing objects in view my invention comprises a plate having inwardly curved end portions, one of which is substantially parallel to the plate and constitutes a catch or pin-point-retaining means and the other has a perforation in its upper part through which the bent portion of the pin-tongue passes, after which the perforated bent portion of the plate is bent downwardly substantially at right angles to the plate to form a hood for the bent portion of the pin-tongue, the other end of the lower arm of said pin-tongue being secured to the plate under the said pin-point-retaining means.

In the drawings which accompany and form a part of this specification and illustrate one embodiment of my invention,—

Figure 1 is a plan view of the front plate before the pin-tongue is attached thereto.

Fig. 2 is a side view of said plate.

Fig. 3 is a side view of the two-part pin-tongue.

Fig. 4 is a plan view of a clasp or lingerie pin embodying my invention, and Fig. 5 is a side view thereof.

In the particular drawings selected for illustrating the preferred embodiment of my invention, 10 is the front plate of a clasp, lingerie pin or the like having two inwardly curving end portions 11, 12, the end portion 12 being substantially parallel to the plate in the finished article so as to form a catch or pin-point-retaining means, and preferably the upper part thereof is provided with a shallow longitudinal groove 13 to prevent the disengagement of the pin-point.

The other end portion is provided with an elongated perforation 14, and the end thereof is notched as indicated at 15.

The pin-tongue consists of spring ma-

terial bent upon itself as shown in Fig. 3 to form an upper arm 16 and a lower arm 17, the end of the former being pointed and that of the latter preferably bent as shown at 18 to conform to the curvature of the bend of the end portion 12 of the plate, the groove 13 preferably being continued from the upper portion of said end down to the plate itself as indicated at 13' to accommodate the said bend 18 of the lower arm of the pin-tongue.

The intermediate portion of the lower arm of the pin-tongue may be corrugated as indicated at 19 so that the pin may be more firmly retained in the fabric through which the upper arm is inserted, such fabric being compressed between the upper and lower arms.

In order to assemble the clasp, the pointed end of the pin-tongue is inserted through the perforation 14 and the upper arm drawn therethrough until the bent portion thereof is in said perforation whereupon the curved end 18 of the lower arm is inserted in the groove 13 formed in the inner surface of the end 12, and said end, which as shown in Fig. 2, is slightly inclined to the plate, is then pressed downwardly until it is parallel, or substantially parallel, to the plate, and then the perforated end is bent downwardly substantially at right angles to the plate to form a hood for the bent portion of the pin-tongue, the notch 15 in the end of said perforated end portion fitting over the lower arm of the pin-tongue as indicated in Fig. 5 in order more firmly to secure the latter in position.

It will be understood that while I have illustrated and described one particular embodiment of my invention, various modifications may be made therein without departing from the spirit of my invention.

I claim,—

1. A clasp comprising a front plate having inwardly curving end portions, one of said end portions being disposed substantially parallel to said plate and constituting a pin-point-retaining means, and the other having a perforation in its upper part, and a pin-tongue of spring material bent upon itself and comprising an upper and a lower arm, the bent portion of said pin-tongue passing through said perforation and the other end of the same being secured to said plate under said pin-point-retaining means.

2. A clasp comprising a front plate having inwardly curving end portions, one of said end portions being disposed substantially parallel to said plate and constituting a pin-point-retaining means, and the other having a perforation in its upper part, and a pin-tongue of spring material bent upon itself and comprising an upper and a lower arm, the bent portion of said pin tongue passing through said perforation, and the perforated end portion being bent downwardly substantially at right angles to said plate to form a hood for said bent portion of said pin-tongue, and the other end of said pin-tongue being secured to said plate under said pin-point-retaining means.

3. A clasp comprising a front plate having inwardly curving end portions, one of said end portions being disposed substantially parallel to said plate and constituting

a pin-point-retaining means, and the other having a perforation in its upper part, and a pin-tongue of spring material bent upon itself and comprising an upper and a lower arm, the bent portion of said pin tongue 25 passing through said perforation, and the perforated end portion being bent downwardly substantially at right angles to said plate to form a hood for said bent portion of said pin-tongue, the end of said perforated end portion being provided with a notch fitting over said lower arm, and the other end of said pin-tongue being secured to said plate under said pin-point-retaining means. 30

In testimony whereof, I have hereunto subscribed my name this 18th day of November, 1922.

CLIFFORD G. KING.
